UNITED STATES PATENT OFFICE.

FREDERICK A. BALLOU, OF NAYATT, AND ROGERS T. STAFFORD, OF EAST PROVIDENCE, RHODE ISLAND, ASSIGNORS TO B. A. BALLOU & CO., INC., OF PROVIDENCE, RHODE ISLAND, A CORPORATION OF RHODE ISLAND.

SHOE STRAP.

Application filed May 7, 1927. Serial No. 189,632.

This invention relates to an improved construction of shoe strap; and has for its object to provide a strap of this character having a portion arranged to extend over the 5 instep of the wearer and a portion to extend forwardly from the instep portion and one or more of the ends of these straps being adapted to be detachably connected to the shoe upper and in addition to being ornamental the strap serves to assist in retaining 10 the shoe in position on the foot of the wearer.

A further object of the invention is to construct this shoe strap in the form of the 15 letter T, the cross strap portion being arranged to extend over the instep and the other portion arranged to extend forwardly, all three ends being preferably detachably connected to the shoe upper.

20 A still further object of the invention is the provision of clamping members on each of these ends whereby the whole strap may be detachably connected as a unit to the edges of the shoe of the wearer if desired.

25 With these and other objects in view, the invention consists of certain novel features of construction as will be more fully described, and particularly pointed out in the appended claims.

30 In the accompanying drawings:

Figure 1 is a perspective view showing our improved shoe strap in position.

Figure 2 show the strap straightened out or in extended position.

35 Figure 3 is an enlarged view partly in section showing the inner and outer links of the chain of which the strap is constructed as arranged to be extended endwise to render the device extendible and flexible 40 so as to yield to the muscular action of the foot of the wearer.

Figure 4 is an enlarged view illustrating an enlarged ornamental central member and showing the chain links as connected to three 45 sides thereof.

Figure 5 is a detailed view illustrating the clamp on one of the strap ends as attached to the edge of the shoe upper.

50 Figure 6 shows the T-shaped arrangement of the strap formed of extendible links.

It is found in practice of advantage to provide a strap arranged to extend over the instep of the wearer and to provide attaching clamps by which the ends of this strap

portion may be detachably connected to the 55 opposite edges of the shoe; also to provide a forwardly extending member on this strap having a clamping member on its end to be attached to the forward portion of the shoe, which latter member in addition to serving 60 as an ornament also serves to retain the cross strap in the desired working position and prevent it from slipping on the foot of the wearer; and the following is a detailed description of the present embodiment of 65 our invention and showing one means by which these advantageous results may be accomplished:

With reference to the drawings, 10 designates the instep strap which is herein shown 70 as being constructed of a plurality of links 11 preferably comprising a plurality of outer box-shaped links 12 and inner slide links 13, the inner and outer members of each link being acted upon by a coiled spring 75 14 to press the two toward closed or contracted position.

The ends of this strap are provided with clamping members 15 each clamp having an outer jaw portion 16 and an inner or under 80 jaw portion 17 which is pivotally connected to the outer jaw member and is normally pressed by spring action toward closed position as more fully described in our copending patent application Se. No. 174,317 filed 85 March 10, 1927. In some cases the connected links of this cross strap may extend from end to end as illustrated in Figure 6, while in other cases an ornamental member 86 18 may be attached to the strap by any suitable means.

In order to retain this cross strap in the desired position and to also provide further ornamentation for the strap, we have formed a forwardly extending strap portion 95 19 which is preferably also constructed of a plurality of chain links similar to those of which the cross strap is constructed, but which may be constructed in any other desired way, and the end portion of this forwardly extending strap portion is also preferably provided with a clasp or clamping member 20 preferably similar to those on the end of the cross strap whereby the same may be attached to the edge portion 21 of 100 105 the shoe upper.

Our improved construction of shoe strap is very simple and practical and is effective

in its operation and by forming the same wholly or in part of extendible links it will accommodate itself to the muscular action of the foot of the wearer while walking or dancing and so prevents cramping and injury to the foot.

The foregoing description is directed solely towards the construction illustrated, but we desire it to be understood that we 10 serve the privilege of resorting to all the mechanical changes to which the device is susceptible, the invention being defined and limited only by the terms of the appended claim.

15 We claim:

A shoe strap comprising an elastic part of a length to extend over the instep of the

wearer to substantially the opposite edges of the shoe upper and having attaching means at its ends to engage the margins of the shoe, 20 and a second part attached to the first part intermediate its ends and extending therefrom forwardly to meet the forward edge of the foot opening, means for securing said second part to the forward margin of the 25 foot opening, said second part being elastic to permit of a limited movement of the instep part of the strap to conform to the muscular action of the foot in walking.

In testimony whereof we affix our signatures.

FREDERICK A. BALLOU.
ROGERS T. STAFFORD.
